PAGE 2

FIG. 3

FIG. 2

FIG. 4

FIG. 5

FIG. 1 is a front perspective view of a flatware display stand embodying our new design, the rear being substantially plain and unornamented;

FIGS. 2 and 3 are, respectively, elevational views of opposite sides thereof;

FIG. 4 is an enlarged elevational view of the rack taken from the front thereof, the broken line representations of flatware being for purposes of illustration only; and

FIG. 5 is an enlarged plan view of the rack taken from the top thereof.

The dominant features of the design reside in the portions shown in full lines.

We claim:

The ornamental design for a flatware display stand, substantially as shown and described.
